SHOULDER CORD

Arthur E. Du Bois and Elizabeth Will, Washington, D. C., assignors to the United States of America as represented by the Secretary of the Army

Application December 4, 1952, Serial No. 22,552

Term of patent 14 years

(Cl. D3—32)

To all whom it may concern:

The invention described herein, if patented, may be manufactured and used by or for the Government for governmental purposes, without the payment to us of any royalty thereon.

Be it known that we, Arthur E. Du Bois and Elizabeth Will, citizens of the United States and residents of the city of Washington, in the District of Columbia, have invented a new, original, and ornamental Design for a Shoulder Cord, of which the following is a specification, reference being had to the accompanying drawing, forming a part thereof.

Figure 1 is a side elevation of a shoulder cord, embodying our new design; and

Figure 2 is a front elevation of the same.

The characteristic features of the design reside in the continuous endless loop composed of two

major lengths of interlocking square knots joined at their upper ends by a plain cord and at their lower ends by a twisted cord, said cords being of lesser diameters than the diameters of the lengths of interlocking square knots, all as shown.

We claim:

The ornamental design for a shoulder cord, substantially as shown and described.

ARTHUR E. DU BOIS.
ELIZABETH WILL.
